(57) CLAIM

The ornamental design for a shoe, as shown and described.

DESCRIPTIONFIG. 1 is a front perspective view of a shoe showing my new design;
FIG. 2 is a bottom view thereof; and,

FIG. 3 is a rear perspective view thereof.

The broken lines immediately adjacent to the photographic area define the bounds of the claimed design and form no part thereof. The broken lines depicting the remainder of the shoe show features that form no part of the claimed design. The unshaded region within the photographic area that is demarcated by broken lines represents a feature that forms no part of the claimed design.
